PLAYING CARD DISTRIBUTOR

Clifford P. Sivertson, Washington, D. C.

Application February 5, 1954, Serial No. 408,481

2 Claims. (Cl. 273—149)

This invention relates to a playing card distributor and has for its primary object to deliver one at a time playing cards from a stack of playing cards in order to assist in dealing.

The above and other objects may be attained by employing this invention which embodies among its features a magazine having a top, said magazine being adapted to receive a stack of playing cards, means mounted in said magazine for advancing the stack of cards contained therein toward the top, said magazine having a card discharge slot extending therethrough adjacent the top, and an ejector carried by the magazine and movable thereacross adjacent the top for engaging the topmost card in the stack of cards and projecting it through the slot.

Other features include a pistol grip carried by the magazine and projecting downwardly and outwardly therefrom adjacent the side thereof remote from the slot, a lever mounted in the pistol grip to move adjacent the magazine, said lever being operatively connected to the ejector for moving said ejector in unison with the movements of the lever, a trigger carried by the lever for movement in a path which lies transversely of and below the magazine, and means operatively connecting the lever to the ejector for moving the ejector in unison with the lever.

Still other features include resilient means carried by the magazine and connected to the trigger for advancing the trigger toward the side of the magazine adjacent the card discharge slot and retracting the ejector relative to the card discharge slot.

In the drawings:

Figure 1 is a perspective view of a playing card distributor embodying the features of this invention;

Figure 2 is a front view thereof;

Figure 3 is an enlarged fragmentary sectional view taken substantially on the line 3—3 of Figure 2;

Figure 4 is a vertical sectional view taken substantially on the line 4—4 of Figure 3;

Figure 5 is a horizontal sectional view taken substantially on the line 5—5 of Figure 4; and

Figure 6 is a horizontal sectional view taken substantially on the line 6—6 of Figure 4.

Referring to the drawings in detail, this improved card distributor comprises a magazine designated generally 10 having a back wall 14, a front wall 16 and a top wall 18. An end wall 20 closes one end of the chamber or magazine, as will be readily understood upon reference to the drawings, and formed in the front wall 16 adjacent the top wall 18 is an elongated slot 22, the upper edge of which lies flush with the underside of the top wall 18 to define a passage through which the topmost card of a stack of cards contained within the magazine may be ejected. As illustrated in the drawings, the top wall 18 is provided intermediate its ends, and substantially midway between opposite ends of the magazine with a transversely extending slot 24, opposite side walls of which carry inwardly extending tongues 26 which define guideways upon which the ejector, to be more fully hereinafter described, is mounted to slide. As illustrated in the drawings, the guideways 26 are extended as at 28 beyond the back wall 14 of the magazine to define a support for the ejector when it is in its retracted position, as shown in Figure 3. As will be readily understood upon reference to Figures 1, 2 and 4 of the draw-

2

ings, the ends of the back and front walls 14 and 16, respectively, are recessed as at 30 to expose the cards of a stack of cards contained within the magazine adjacent one end of said stack.

Carried by the front and back walls and extending therebetween adjacent the open end of the magazine 10 and below the recesses 30 is a pivot bar 32 on which is mounted for rocking movement within the magazine 10 a lever arm 34 which forms a support for a false bottom 36 mounted within the magazine and carrying a depending stop 38 which serves to retain the false bottom in proper position on the arm 34. Torsion springs 40 are looped about the pivot bar 32 adjacent opposite ends thereof and these springs are provided with downwardly inclined arms 42 which bear on the bottom 12. Arms 44 are carried by the torsion springs 40 and extend upwardly above the bottom 12 and carried by the arms 44 and extending therebetween is a cross bar 46 which engages the lever arm 34 and urges it upwardly to advance the false bottom 36 toward the top wall 18. The top wall 18 and the false bottom 36 are respectively recessed as at 48 and 50, respectively, above the pivoted end of the lever arm 34 to facilitate the introduction and extraction of a stack of playing cards into the space between the false bottom 36 and the top 18.

Mounted for sliding movement in the slot 24 on the guides 26 is an ejector element designated generally 52 which comprises a carriage 54 having grooves 56 extending longitudinally thereof and opening through opposite side edges to receive the guides 26 by means of which the carriage 52 is mounted for sliding movement in the slot 24. Carried by and projecting downwardly from the underside of the carriage 54 adjacent one end thereof is an ejector lug 58 which is adapted to engage the topmost card of a stack of cards in the magazine M defined between the top 18 and false bottom 36 so that as the ejector member 52 is moved through the slot 24, the topmost card in the stack of cards will be projected through the slot 22 in the front wall 16 of the device. A suitable barrel 60 is carried by the carriage 54 and extends upwardly therefrom intermediate the ends thereof and is provided with a longitudinal bore which extends transversely relative to and above the slot 24.

Carried by the distributor body 10 and projecting downwardly and rearwardly adjacent the bottom and rear walls 12 and 14, respectively, is a hollow pistol grip handle 62 having a transversely extending pivot pin 64 extending therethrough adjacent its junction with the distributor 10 upon which is mounted for rocking movement in an arcuate path which intersects the slot 24 and lies perpendicular to the longitudinal axis of the distributor a lever arm 66 carrying adjacent one end an arm 68 to which is pivotally connected a link 70 having inwardly extending fingers which enter the bore in the barrel 60 and thus pivotally connect the lever to the ejector member 52. Thus, it will be evident that movement of the lever 66 about the pivot 64 will advance the arm 68 toward the distributor 10 so as to move the ejector member 52 transversely across the magazine M to eject the topmost card on the stack S of the cards contained in the magazine through the slot 22. A trigger 72 is connected at 74 to the lever 66 on the side of the pivot pin 64 remote from the arm 68 and slides between depending flanges 76 carried by the handle 62 and extending across the underside of the bottom 12 of the ejector 10 which defines the guideways for the trigger 72. Formed in the upper surface of the trigger 72 and extending downwardly and rearwardly from the end thereof remote from the handle 62 is a recess 78 in the back wall of which is anchored one end of a retractile coil spring 80, the opposite end of which is anchored in the bottom wall 12 adjacent its junction with the front wall 16. It will thus

be seen that the ejector member 52 will be held in retracted position through the medium of the link 70, arm 68, lever 66, trigger 72 and spring 80.

Formed in the back wall 14 and lying substantially concentric about the pivot pin 32 is a slot 82 through which projects an arm 84 which is carried by the lever member 34 and carries at its outer end a thumb piece 86 by means of which the lever 34 may be moved against the effort of the spring arms 44 to enable the false bottom 36 to move away from the top 18 and facilitate the introduction into, or extraction from the chamber M of a stack of cards. Obviously, by moving the lever arm 34 against the effort of the spring arms 44, the cards in a stack of cards contained in the chamber 10 may be so freed that by gripping the cards adjacent opposite sides through the openings 30 in the back and front walls 14 and 16, respectively, a shuffling of the cards may be accomplished.

In use, the pistol grip 62 is held in the hand with the thumb on the thumb piece 86 to move the lever arm 34 against the effort of the spring arms 44 to permit the false bottom 36 to move away from the top 18. With the parts in this position, a stack of cards is introduced into the magazine and upon releasing the pressure on the thumb piece 86, the stack of cards will be moved under the influence of the spring arms 44 to yieldingly advance the stack of cards toward the top 18. With the cards shuffled and the stack elevated into contact with the top wall 18, pressure is exerted on the trigger 72 to move it against the effort of the spring 80 and cause the lever 66 and arm 68 through the medium of the link 70 to advance the carriage 54 toward the slot 22 in the front wall 16 of the magazine M. As the carriage starts to move, the ejector 58 will engage the topmost card in the stack of cards and advance it through the slot 22. By repeating the operation, the cards may be ejected from the stack of cards S and distributed one at a time on a table before a group of players distributed therearound. Obviously, in this manner uniform distribution of the cards is accomplished with but a minimum of effort on the part of the dealer.

While in the foregoing there has been shown and described the preferred embodiment of this invention, it is to be understood that minor changes in the details of construction, combination and arrangement of parts may be resorted to without departing from the spirit and scope of the invention as claimed.

What is claimed is:

1. A card distributor comprising a magazine for a stack of cards including a top wall, a bottom wall, a back wall, and a front wall having an elongated discharge slot extending in a plane closely spaced from and paralleling the top wall, through which slot the topmost card of the stack may be ejected; means in the magazine for urging the stack toward the top wall, for positioning the topmost card in said plane; a pistol grip handle rigid with and depending from the magazine substantially at the juncture between the back and bottom walls, said handle being of channel shaped cross section at least at the upper end thereof, said upper end of the handle opening upwardly rearwardly of the back wall of the magazine, the handle also opening forwardly below the bottom wall; a lever having one end portion extending through the open upper end of the handle, said end portion of the lever being pivotally connected to the handle, the lever extending upwardly from the handle rearwardly of the back wall of the magazine and swinging about the axis of its pivotal connection to the handle in a plane normal to the plane of said slot; an ejector element slidably mounted in the top wall and including a lug projecting downwardly therefrom in said plane of the slot; a link pivotally connected between said element and the upper end of the lever, said lever swinging about the axis of its pivotal connection to the handle between opposite extreme positions, in one of which the lug is flush with the back wall to engage against a back-wall-engaging edge of the topmost card and in the other of which the lug is flush with the front

wall to shift the topmost card through the slot forwardly out of the magazine, for free fall of the ejected card from the magazine, said handle including side flanges projecting forwardly from the side walls of the handle and secured to the bottom wall of the magazine to form, in cooperation with said bottom wall, a guideway opening at one end into the handle adjacent the lower end portion of the lever; and a trigger slidably mounted at one end in said guideway and pivotally connected at its other end to said lower end portion of the lever, said trigger moving into the forwardly opening handle responsive to pressure exerted against the trigger by the finger of a hand gripping the handle, the connection of the trigger to the lever being disposed below the axis about which the lever pivots on the handle, whereby on movement of the trigger into the handle said trigger will rock the lever in a direction to swing the upper end thereof toward the magazine, to shift the lever to said other extreme position thereof.

2. A card distributor comprising a magazine for a stack of cards including a top wall, a bottom wall, a back wall, and a front wall having an elongated discharge slot extending in a plane closely spaced from and paralleling the top wall, through which slot the topmost card of the stack may be ejected; means in the magazine for urging the stack toward the top wall, for positioning the topmost card in said plane; a pistol grip handle rigid with and depending from the magazine substantially at the juncture between the back and bottom walls, said handle being of channel shaped cross section at least at the upper end thereof, said upper end of the handle opening upwardly rearwardly of the back wall of the magazine, the handle also opening forwardly below the bottom wall; a lever having one end portion extending through the open upper end of the handle, said end portion of the lever being pivotally connected to the handle, the lever extending upwardly from the handle rearwardly of the back wall of the magazine and swinging about the axis of its pivotal connection to the handle in a plane normal to the plane of said slot; an ejector element slidably mounted in the top wall and including a lug projecting downwardly therefrom in said plane of the slot; a link pivotally connected between said element and the upper end of the lever, said lever swinging about the axis of its pivotal connection to the handle between opposite extreme positions, in one of which the lug is flush with the back wall to engage against a back-wall-engaging edge of the topmost card and in the other of which the lug is flush with the front wall to shift the topmost card through the slot forwardly out of the magazine, for free fall of the ejected card from the magazine, said handle including side flanges projecting forwardly from the side walls of the handle and secured to the bottom wall of the magazine to form, in cooperation with said bottom wall, a guideway opening at one end into the handle adjacent the lower end portion of the lever; and a trigger slidably mounted at one end in said guideway and pivotally connected at its other end to said lower end portion of the lever, said trigger moving into the forwardly opening handle responsive to pressure exerted against the trigger by the finger of a hand gripping the handle, the connection of the trigger to the lever being disposed below the axis about which the lever pivots on the handle, whereby on movement of the trigger into the handle said trigger will rock the lever in a direction to swing the upper end thereof toward the magazine, to shift the lever to said other extreme position thereof, said trigger having a resilient, yielding connection to said bottom wall of the magazine tensioned to oppose movement of the trigger into the handle.
